Primary Examiner — Darcey E Gottschalk*(74) Attorney, Agent, or Firm* — Sterne, Kessler, Goldstein & Fox P.L.L.C.(57) **CLAIM**

The ornamental design for a mouthpiece as shown and described.

DESCRIPTION

The FIGURE is a top isometric view of a mouthpiece showing the claimed design.

The broken lines in the FIGURE show portions of the mouthpiece that form no part of the claimed design. Portions of the mouthpiece that are not visible in the FIGURE are not claimed.

1 Claim, 1 Drawing Sheet(56)
